UNITED STATES PATENT OFFICE

162,181

AIR DISTRIBUTION OUTLET

Walter W. Kennedy, Rockford, Ill.

Application May 19, 1948, Serial No. 146,445

Term of patent 14 years

(Cl. D62—4)

To all whom it may concern:

Be it known that I, Walter W. Kennedy, a citizen of the United States, residing at Rockford, in the county of Winnebago and State of Illinois, have invented a new, original, and ornamental Design for an Air Distribution Outlet, of which the following is a specification, reference being had to the accompanying drawings, forming a part thereof.

In the drawings:

Figure 1 is a perspective view of an air distribution outlet, embodying my new design.

Fig. 2 is a bottom view.

Fig. 3 is a section taken along line 3—3 of Fig. 2.

I claim:

The ornamental design for an air distribution outlet, substantially as shown.

WALTER W. KENNEDY.
